UNITED STATES PATENT OFFICE

142,790

DESIGN FOR A GAME BOARD

Cargill W. Redpath, Kansas City, Mo.

Application June 4, 1945, Serial No. 119,899

Term of patent 14 years

(Cl. D34—5)

To all whom it may concern:

Be it known that I, Cargill W. Redpath, a citizen of the United States and a resident of Kansas City, in the county of Jackson, State of Missouri, have invented a new, original, and ornamental Design for Game Boards, of which the following is a specification, reference being had to the accompanying drawing, forming a part thereof.

In the drawing:

I claim:

The ornamental design for a game board, substantially as shown.

CARGILL W. REDPATH.
